UNITED STATES PATENT OFFICE.

CHRISTOPHER KAMMERER, OF BOSTON, MASSACHUSETTS.

VALVE-CONTROLLING APPARATUS.

SPECIFICATION forming part of Letters Patent No. 451,937, dated May 12, 1891.

Application filed November 7, 1890. Serial No. 370,615. (No model.)

To all whom it may concern:

Be it known that I, CHRISTOPHER KAMMERER, of Boston, county of Suffolk, State of Massachusetts, have invented an Improvement 5 in Valve-Controlling Apparatus, of which the following description, in connection with the accompanying drawings, is a specification, like letters on the drawings representing like parts.

This invention has for its object to provide 10 an apparatus of novel construction, as will be described, in which a flexible diaphragm is normally acted upon on one side by hydrostatic pressure, which hydrostatic pressure in 15 the operation of the apparatus is neutralized by a counterbalancing pressure, as will be hereinafter set forth.

My invention, among other things, is especially adapted for controlling the movement 20 of a valve, which may be the outlet-valve of a steam-trap.

The particular features of my invention will be pointed out in the claims at the end of this specification.

Figure 1 is a vertical section on line $x-x$, Fig. 2, of a steam-trap embodying my invention; Fig. 2, a top or plan view of the steam-trap shown in Fig. 1; Fig. 3, a modification in section to be referred to; and Fig. 30 4, a sectional detail on line $x'-x'$, Fig. 3.

The apparatus shown in Fig. 1 as embodying my invention represents a steam-trap adapted to be used in connection with any form of steam-chamber, such, for instance, 35 as a radiator coil or vessel. (Not herein shown.)

In accordance with my invention a flexible diaphragm A, preferably composed of a plurality of sheet-metal disks or plates, there being five herein shown, (marked 2 3 4 5 6), is 40 secured within a shell or case A', so as to divide the same into two chambers a a' . The case or shell A', as herein represented, is made in two parts a^2 a^3 , secured together by bolts a^4 . The metallic disk or plate 2 of 45 the flexible diaphragm is made of greater diameter than the remaining plates or disks to be clamped between the parts a^2 a^3 of the case or shell A', the said disk being fastened to the disk 3 by a coupling-sleeve a^5 , screwed 50 into nipples a^6 a^7 , fastened to the under side of the disk 2 and to the top of the disk 3, respectively. The disk 3 is soldered or other-

wise fastened at its circumference or edge to the disk 4, which is secured to the disk 5 by a coupling-sleeve a^8 , screwed into threaded nipples a^9 a^{10} , secured to the disks 4 5; respectively, the disk 5 being soldered or otherwise fastened at its circumference or edge to the disk or plate 6, having soldered or otherwise fastened to it a weight, herein shown as a plate a^{12} , preferably a metal plate. The plate a^{12} , as shown in Fig. 1, has fastened to it, it being herein shown as screwed into it, a rod b^x , extended through the sleeves a^5 a^8 beyond the disk 2 into the chamber a' , the said rod constituting a valve, as will be described.

The part a^3 of the case or shell A' has secured to or forming part of it a pipe b , preferably of considerable diameter, and preferably enlarged at its upper end to form a chamber b' . The pipe b has secured to its upper end, as herein shown, a cap b^2 , provided with a threaded nipple b^3 , by which the trap may be secured to the radiator-coil or other vessel in which the condensed steam is to be 75 trapped. The pipe b contains within it a duct (shown as a pipe b^5) of substantially small diameter, provided at its upper end with a funnel-shaped mouth b^6 , preferably of larger diameter than the nozzle b^3 , so that the water of 80 condensation may be discharged into the funnel-shaped mouth b^6 . The pipe b^5 at its lower end is connected, as herein shown, to a hollow arm b^7 , represented as an integral part of the upper part a^3 of the case A', the said hollow arm forming a continuation of a passage b^8 in the part a^3 , which registers with a passage b^9 in the part a^4 of the case, the latter communicating with the chamber a . The hollow arm b^7 and passages b^8 b^9 form practically 85 a continuation of the pipe b^5 . The pipe b communicates with the chamber a' .

The upper part a^3 of the case or shell A', as shown in Fig. 1, has secured to it a valve casing or fitting B, having an inlet-port c , 90 communicating with an outlet port or opening c' in the pipe b , to which the fitting B is also secured, as by bolts c^2 , indicated by dotted lines, Fig. 1, the said valve casing or fitting having an outlet-port c^3 , which in practice may be connected to any suitable receptacle. (Not herein shown.)

The valve casing or fitting B is provided with a port or opening c^4 between the inlet-

port c^3 and the outlet-port c^3 , and the port c^4 is normally closed by a valve c^6 , having its stem c^7 connected, as shown in Fig. 1, to a piston c^8 , movable in a cylindrical extension 10 of the fitting B. The piston c^8 is provided, as shown, with an opening or passage c^9 , extended through it longitudinally, as will be hereinafter described.

The cylinder 10 of the fitting B is extended 10 through the part a^3 of the case or shell A', and the said cylinder is provided with a head c^{12} , having a port or opening c^{13} extended through the said head and, as herein shown, through a nozzle c^{14} on the under side of the head substantially in line with the rod b^x , the latter constituting a valve by which the port c^{13} may be opened and closed, as will be described.

The valve c^6 is normally closed, as shown, 20 by a spiral spring c^{15} , surrounding the upper portion of the valve-stem c^7 , and having its upper end extended into a recess in a cap 13 closing the end of the upper cylindrical extension of the valve-fitting B.

25 The operation of my invention, as embodied in the steam-trap herein described is as follows: The water of condensation from the radiator or other vessel passes through the nozzle b^3 into the pipe b^5 and descends through 30 the said pipe, hollow arm b^7 , passages $b^8 b^9$, into the chamber a . The water fills the chamber a and then gradually fills up the passages $b^8 b^9$, arm b^7 , and pipe b^5 . As the water rises in the pipe b^5 the flexible diaphragm A is 35 acted upon its under side by hydrostatic pressure, due to the column of water in the pipe b^5 , and the said diaphragm is lifted, thereby bringing the valve or rod b^x up in contact with the nozzle c^{14} and shutting off 40 communication between the chamber a' and the port c^{13} . The valve c^6 is at such times closed by the spring c^{15} . The water of condensation continues to flow or drop into the pipe b^5 until it has filled the same, and there- 45 after the water of condensation overflows the pipe b^5 and descends through the pipe b into the chamber a' . The water of condensation is thus trapped until the column of water in the pipe b has attained a height sufficient to 50 neutralize or counterbalance the hydrostatic pressure upon the under side of the dia- phragm. The pressure upon the opposite sides of the diaphragm now being equal, the weight a^{12} draws the diaphragm downward and removes the valve or rod b^x , so as to 55 uncover the port c^{13} and permit the water of condensation in the chamber a' to pass through the port c^{13} into the cylinder 10 of the fitting B and act on the pistons c^8 , moving the latter upward and opening the valve c^6 . As soon as 60 the valve c^6 is opened the water in the pipe b above the outlet-port c' for the said pipe will flow through the ports $c^4 c^8$, and, if desired, into a waste or storage tank. (Not shown.) As 65 soon as sufficient water in the pipe b has been discharged so that the pressure on the under side of the diaphragm predominates, the dia-

phragm is raised and the valve or rod b^x seated, thus cutting off the pressure upon the under side of the piston c^8 and permitting the 70 spring c^{15} to seat the valve c^6 and close the port c^4 , thereby stopping the discharge of water from the pipe b . The valve c^6 is gradually seated as the water in the cylinder 10 escapes through the passage c^9 in a small quantity or 75 stream, the water in the cylinder 10 acting as a cushion for the piston c^8 and valve c^6 . The valve c^6 remains closed until the pressure of the hydrostatic column on the under side of the diaphragm is again balanced by the pressure on the opposite or upper side of the dia- phragm. The piston c^8 acts in the capacity of an auxiliary valve to operate the main valve, and, while I may prefer to employ the construction shown in Fig. 1, I do not desire 85 to limit my invention in this respect, as other forms of valve may be employed—for instance, as shown in Figs. 3 and 4.

Referring to Fig. 3, the valve-fitting is shown as provided with an inlet-port f , through which is extended the stem f' of a piston-valve provided with three pistons $f^2 f^3 f^4$, adapted to register with ports connecting the inlet-port f with the outlet or discharge port f^5 . The valve-fitting is secured to the part a^3 , and the valve-stem f' is fastened to the diaphragm A and is moved thereby to open and close the ports in the valve case or fitting. The valve is normally seated by the spring c^{15} , the pressure of which may be adjusted, as herein shown, by a screw-threaded rod f^7 . The piston-valves $f^2 f^3 f^4$ are connected, as herein shown, by webs f^8 , forming practically a continuation of the valve-stem f' .

I claim—

1. The combination, with a shell or case made in two parts, of a diaphragm consisting of a plurality of disks or plates, one of the said disks being of larger diameter than the remaining disks of the diaphragm and secured between the parts of the case or shell to divide the said case or shell into chambers, a pipe communicating with one of said chambers and adapted to contain a hydrostatic column, and a second pipe communicating with the other chamber, substantially as described.

2. The combination, with a shell or case, of a diaphragm secured therein to form chambers, a pipe communicating with one chamber and adapted to contain a hydrostatic column, a second pipe communicating with the other chamber, a valve case or fitting having an inlet-port c , communicating with one of the said pipes and with a port c^{13} , communicating with one of the said chambers, and provided with an outlet or discharge port, and a valve to control communication between the inlet-port c and the outlet-port of the valve case or fitting, substantially as described.

3. The combination, with a shell or case, of a diaphragm secured therein to form chambers, a pipe communicating with one chamber and adapted to contain a hydrostatic col-

umn, a second pipe communicating with the other chamber, a valve case or fitting B, provided with cylindrical extensions 10 12 and having an inlet-port c, communicating with 5 one of the said pipes, and provided with an outlet-port, a port c⁴ between said inlet and outlet ports, a valve to control the port c⁴, a piston c⁸ connected to said valve, a port c¹³, connecting the cylinder 10 with one of the 10 said chambers, a valve b^x, secured to the diaphragm and controlling the port c¹³, and means to seat the valve controlling the port c⁴, substantially as described.

4. The combination, with a shell or case 15 composed of two parts a² a³, of a diaphragm composed of a plurality of disks or plates, one of which is secured between the said parts to form chambers a a', a weight attached to said diaphragm, a pipe b⁵, communicating 20 with the chamber a, a pipe b, inclosing the pipe b⁵ and communicating with the chamber a', a valve-fitting B, secured to the part a³ and provided with a port-opening c¹³, and having an inlet-pipe c, communicating with

the pipe b, a valve c⁶ in said fitting to control a port leading from the inlet-port c to an outlet-port c³ for the said fitting, an auxiliary valve c⁸, connected to the valve c⁶, a spring to seat the valve c⁶, and a valve b^x, attached to and operated by the diaphragm to close 25 the port-opening c¹³, substantially as described.

5. In a steam-trap, the herein described diaphragm, it consisting of a plurality of metallic disks or plates, independent threaded 35 nipples secured to independent disks or plates, and a coupling-sleeve inserted into two of the said independent nipples to unite the said threaded nipples together, substantially as described.

In testimony whereof I have signed my name to this specification in the presence of two subscribing witnesses.

CHRISTOPHER KAMMERER.
